UNITED STATES PATENT OFFICE

JOSEPH W. DUSEK, OF WESSINGTON SPRINGS, SOUTH DAKOTA

HUSKING-MACHINE SNAPPING ASSEMBLY

Application filed October 5, 1928. Serial No. 310,588.

The present invention relates to an improved snapping assembly for use with corn huskers and has for its prime object to provide means for maintaining the snapping rows clean while in operation.

Another very important object of the invention resides in the provision of a pair of smooth wooden rollers, one below each snapping rolls and rotating in the same direction therewith so as to maintain the snapping rolls clean of grass, and other extraneous material or the like which may be picked up by the snapping row.

A still further very important object of the invention resides in the provision of an improved structure of this nature which is simple in its details of construction, strong and durable, inexpensive to manufacture, and thoroughly efficient and reliable in operation.

With the above and numerous other objects in view as will appear as the description proceeds, the invention resides in certain novel features of construction, and in the combination and arrangement of parts as will be hereinafter more fully described and claimed.

In the drawing:

Figure 1 is an elevation of a snapping assembly embodying the features of my invention,

Figure 2 is a perspective view of one of the cleaning rolls,

Figure 3 is a fragmentary top plan view of the assembly showing the relationship of the snapping rolls and cleaning rolls,

Figure 4 is a plan view showing the lower ends of the cleaning rolls,

Figure 5 is a rear elevation of the assembly showing particularly the gearing, and

Figure 6 is a transverse section through the two snapping rolls and the two cleaning rolls.

Referring to the drawing in detail it will be seen that numerals 5 denote snapping rolls of conventional or any preferred form journaled in the usual well known manner between brackets 6 and 7 on the center 8.

Flanged cylindrical rolls 9 are provided with ends 10 tapered toward their extremi-

ties and these rolls 9 are journaled between extensions 6' of brackets 6 and extensions 7' of brackets 7 so that one roll 9 is located immediately below each snapping roll 5.

The lower ends of the cleaning rolls 9 terminate slightly rearwardly of the lower ends of the snapping rolls 5. The location of the tapered ends 10 prevent them from interfering with the proper operation of the snapping rolls in initially picking up the corn stalks.

Gears 11 are operatively connected with the rear ends of the rolls 5 and the gears 12 are operatively connected with the rear end of the rolls 9. Gears 14 mesh with the gears 11 and 12 so as to cause the rolls 9 to rotate in the same direction with the rolls 5 that is the roll 9 under its respective roller 5 rotates in the same direction therewith.

As is well known the two snapping rolls 70 rotate in opposite direction from each other and therefore the rolls 9 will operate in opposite direction from each other. In operation as the corn stalks and foreign matter are picked up by the lower ends 10 of the snapping rows, this foreign matter becomes entangled on the teeth or ridges provided on the snapping rolls and causes them to become very inefficient so that they set up an unnecessary amount of friction.

With my improved cleaning rolls 9 any such matter will be taken from the snapping rolls and dumped on the ground and thus the snapping rolls will be maintained clean at all times thereby doing away with a lot of unnecessary friction and work which usually has to be overcome.

Thus the husking machine as a whole will operate with less power, and, of course will operate more efficiently.

It is thought that the construction, operation and advantages of this invention will now be quite apparent to those skilled in this art without a more detailed description thereof.

The present embodiment of the invention has been disclosed in considerable detail merely for the purposes of exemplification since in actual practice it attains the features of advantages enumerated as desirable 100

in the statement of the invention and the above description.

It will be apparent that changes in the details of construction, and in the combination and arrangement of parts may be resorted to without departing from the spirit or scope of the invention as hereinafter claimed or sacrificing any of its advantages.

Having thus described my invention, what I claim as new is:

- 10 1. In a snapping assembly, a pair of snapping rolls, a pair of smooth cleaning rolls disposed one under each snapping rolls, gearing connecting the rolls for simultaneous rotation with each snapping roll rotating in the same direction with its respective cleaning roll, the cleaning rolls at their lower ends terminating rearwardly of the snapping rolls.
- 15 2. In a snapping assembly, a pair of snapping rolls, a pair of smooth cleaning rolls disposed one under each snapping rolls, gearing connecting the rolls for simultaneous rotation with each snapping roll rotating in the same direction with its respective cleaning roll, the cleaning rolls at their lower ends terminating rearwardly of the snapping rolls, the lower ends of the cleaning rolls being tapered toward their extremities.
- 20 3. In a snapping assembly, and in combination, a pair of spaced apart brackets, a pair of snapping rolls between said brackets, each of said brackets being provided with downwardly and inwardly directed extensions, a pair of flanged cylindrical cleaning rolls journaled between said bracket extensions, one below each snapping roll, said cleaning rolls at one end tapering toward their extremities, the tapered ends of said cleaning rolls terminating rearwardly of the adjacent ends of said snapping rolls, and gearing operatively connecting the rolls so that the snapping rolls rotate in opposite direction to each other and each cleaning roll rotates in the same direction with its respective snapping roll.
